ELECTRIC CLOCK SYSTEM

Oscar H. Dicke, Rochester, N. Y., assignor to International Business Machines Corporation, New York, N. Y., a corporation of New York

Original application December 14, 1938, Serial No. 245,700, now Patent No. 2,313,466, dated March 9, 1943. Divided and this application January 18, 1943, Serial No. 472,698

8 Claims. (Cl. 58—24)

1

The present invention relates to time control systems and more particularly to time clock systems driven by synchronous motors for punching or printing on a time card the time of arrival and departure of an employee to and from his place of employment, indicating time in railway stations, schools and office buildings, and the like.

In systems of the above type the secondary clocks may be corrected in the sixtieth minute, in that extreme accuracy in the last minute is not important.

In accordance with the present invention a slow secondary clock is advanced by a second or auxiliary synchronous motor which is connected to the time shaft by a gear train having a higher gear ratio so as to rotate the time shaft at a higher speed; or is corrected by the same motor by operating it at a higher speed from the same source of alternating current during the correcting period so as to make the time shaft run faster during correction of a slow clock. In accordance with the present invention a fast clock is corrected by stopping the secondary clock at a certain time indicating point and to again allow it to advance when the master clock reaches a corresponding time indicating point.

One of the objects of the present invention resides in the employment of one or more synchronous alternating current motors in each secondary clock and to correct such secondary clock without the use of costly relays, electro-magnetic setting means or the like, synchronous motors being less costly to build than relays.

Another object of the present invention is to render the secondary clocks very quiet not only during the clock advancing period but also during the clock correcting period.

Another object of the present invention resides in the provision of novel master clocks in which one element of the master clock used for operating clock correcting contacts is always in substantial synchronism with the secondary clocks in spite of the fact that the secondary clocks are at rest during alternating current cessation, such current being derived from a commercial power system having its frequency regulated to correctly manifest passing of time.

Other objects of the present invention reside in the provision of master clocks in which joint action of escapement mechanisms and synchronous motors driven by alternating current of regulated frequency correctly manifest the passing of time and in which the master clock time shaft is ad-

vanced in accordance with current cycle passage during the presence of alternating current.

Another object of the present invention resides in the provision of means to accelerate a master clock when it is tardy with respect to a synchronous motor and to retard such master clock when it is fast with respect to such synchronous motor during the presence of alternating current and to adjust its time measuring mechanism to normal during a cessation of alternating current. The alternating current mentioned being derived from a source having its frequency regulated to manifest accurately the passing of time.

Another object of the present invention resides in the provision of a plurality of line circuits connecting a master clock and one or more secondary clocks, these circuits being energized in sequence by contacts operated by the master clock, and to provide circuit selecting means for each secondary clock, which secondary clock has a high speed driving circuit and a low speed driving circuit, such that the high speed driving circuit is connected to the then energized line circuit when the secondary clock is slow, but the low speed driving circuit is so connected when the secondary clock is correct. This means also acts to hold the secondary clock at stop when it is fast.

Other objects, purposes and characteristics and their advantages will appear from the following description when taken in connection with the drawings and from the drawings themselves in which:

Fig. 1 shows a form of the invention in which the master clock comprises a time shaft driven during current presence by a synchronous motor and during current cessation by a normally braked escapement clock, and in which the secondary clock includes a time shaft driven by two different synchronous motors through gear trains having different gear ratio;

Fig. 1A shows how a push button manually operated may correct a secondary clock;

Fig. 2 illustrates a modified master clock from that shown in Fig. 1 for controlling a secondary clock such as illustrated in Fig. 1, but through the medium of a single circuit, rectifiers being used to isolate two different currents into separate synchronous motors, and in which the master clock is automatically regulated from time to time so as to cause it to run in accordance with the rate of cycle passage only so long as there is no current cessation; and

Fig. 3 shows a two speed synchronous motor which constitutes either a two pole or a four pole

motor depending on which of its two circuits is energized.

In accordance with the present invention it is proposed to employ or have available a commercial alternating current power distributing system delivering current of regulated frequency, that is, current having its average frequency regulated to correctly manifest time by cycle passage or summation. In such case the master clock is of a construction to be regulated (Fig. 2) so as to run in synchronism with alternating current cycle passage, or by correcting a master electric clock in accordance with the duration of a current cessation during each current cessation (Fig. 1). The secondary clocks may be used as tower clocks by using a separate unit for each dial, to operate record sheets, as bell ringers or for any other program purpose.

The inventions disclosed in this application are improvements over the inventions disclosed in my prior applications Ser. No. 365,584 filed May 23, 1929 now Patent No. 2,248,164 granted July 8, 1941; Ser. No. 441,109 filed April 2, 1930, now Patent No. 2,331,267 granted October 5, 1943; Ser. Nos. 729,079 and 729,080 filed June 5, 1934, and now respectively Patent Nos. 2,248,165 and 2,185,334 granted respectively on July 8, 1941 and January 2, 1940; Ser. No. 239,538 filed November 8, 1938, now Patent No. 2,359,973 granted October 10, 1944 and the application of Robert H. Dicke Ser. No. 39,146, filed September 4, 1935, now Patent No. 2,151,317, granted March 21, 1939. This application is a division of my prior application Ser. No. 245,700, filed December 14, 1938, now Patent No. 2,313,466, granted on March 9, 1943.

It is also proposed to have secondary clocks of extremely simple construction. It is found that it is more economical to add an auxiliary motor than to add a relay, or an electrically operated clutch or gear shift. It is also proposed to employ contacts to temporarily stop the secondary clock by opening the motor circuit to correct a fast secondary clock.

Fig. 1.—Structure.—Referring to Fig. 1, the system shown therein is in certain respects different from that claimed in the parent patent particularly in that all corrections of secondary clocks are made at the end of the first hour, or some other time interval, as manifested by the master clock, that is, there is no repeated correction as is the case in the parent patent.

In this form of my invention the master clock and the secondary clocks, only one having been shown structurally are very much alike. That is, each includes a rotatable gear box containing reduction gearing including pinions 192, 194 and gears 193 and 195, the gear boxes G¹ and G² being preferably oil filled. This reduction gearing preferably including sufficient friction or some worm gears, so that if the gear box is rotated and the synchronous motor whose rotor 196 projects from the gear box is not energized this rotor will be rotated at the same speed as the gear box, that is, will be stationary with respect to the gear box.

Referring to Fig. 1 the gear boxes G¹ and G² are pivotally mounted in stationary frames F¹, F², F³ and F⁴. To one end of these gear boxes is fastened a gear 140¹ or 140² which is preferably of slightly larger diameter than the gear box diameter. Concentric with and mounted within one of the bearings of the gear box is a motor shaft 141¹ or 141² on which is mounted the rotor 196 of a synchronous motor, these motors having been designated SM¹⁰ and SM¹¹. Concentric 75

with and mounted within the other bearing of the gear boxes G¹ and G² is a minute shaft (1 R. P. H.) designated 142¹ for the master clock and 142² for the secondary clock these minute shafts carry insulating cams K¹² and K¹³, respectively. The gear ratio of the pinions 192—194 and gears 193—195 within the gear boxes G¹ and G² is such that if these gear boxes are held stationary and the synchronous motors SM¹⁰ and SM¹¹ are rotated at synchronous speed by current from the regulated frequency current source, the minute shafts 142¹ and 142² will rotate clockwise at a speed of one revolution per hour (1 R. P. H.).

The gear 140¹ of the master clock MC¹ is at times, namely, during power failures, driven by any suitable escapement clock including preferably a pendulum 144 having a magnetic bob 144^a, an escape wheel 145, a driven pinion 146, and gear reduction means converionally indicated by the pinions 146 and 148, and the gears 140¹ and 147. This escapement clock also includes a main spring 150 anchored to a hand winding ratchet wheel 151 driving the gear 141. This ratchet wheel 151 is kept from unwinding by the ratchet pawl 152 and may be hand wound by the key 153. Suitable electric motor winding means such as shown in my prior applications above referred to may be used if desired. The pendulum 144 is normally, that is when alternating current is available, held at rest, or is braked, by the electro-magnet 154—155 having its projecting legs surrounded individually by slugs or short circuited rings 156 of low resistance. The winding 155 of this electro-magnet is normally energized by direct current derived through the medium of a rectifier RI² from the regulated alternating current source. The slugs or bucking coils 156 and the rectifier RI² are used to render the electro-magnet slow-releasing. This slow releasing feature is employed to cause the escapement clock mechanism to drive the gear box G¹ about its pivot for a slightly shorter time than the actual current cessation in order that the shaft 142¹ may accurately indicate standard time after a current cessation. In this connection it is desired to point out that a synchronous motor of the kind contemplated, and in fact any commercial synchronous motor, will coast for a time so that it will not be stationary during the entire current cessation. It has been observed that such a synchronous motor will, if deenergized for one second, be tardy only to the extent of about a half second. The slugs 156 are of such resistance that a current cessation of say two seconds will cause the two pole rotor 196 to coast thirty revolutions (one-half second) and will cause the escapement clock to operate for one and one-half seconds.

Referring now to the secondary clock of Fig. 1, the gear 140² is at times, namely when the secondary clock is being corrected, driven by an auxiliary synchronous or induction motor M¹ through the medium of a gear train including pinions 157 and 158 and gears 159 and 140². The gear ratio of this gear train is preferably such that if the motor M¹ having a rotor 166 is operated at normal speed and the synchronous motor SM¹¹ is deenergized, the shaft 142² and cam K¹³, having a clock hand 191 indicated thereon, will be rotated at about sixty times normal speed, that is, at 60 R. P. H. instead of 1 R. P. H. The synchronous motor SM¹¹ may drive the shaft 142² in exactly the same way as synchronous motor SM¹⁰ may drive shaft 142¹.

Operation Fig. 1.—Normally, that is when alternating current of regulated frequency is avail-

able, the alternating current from the regulated source energizes the brake magnet 164-168 and holds the escapement portion of the master clock MC¹ at rest. At the same time the synchronous motor SM¹⁰ drives the shaft 142¹ and the cam K¹² at 1 R. P. H. through the medium of the gear reduction 192-195 within the then stationary gear box G¹. Also, this alternating current of regulated frequency flows through contacts 160-161 through the line L¹, through winding of synchronous motor SM¹¹, and through common return wire C¹, back to the power line, and causes the shaft 142² and the cam K¹³ to be rotated at 1 R. P. H. When the master clock cam K¹² reaches the 59:00 minute position the contacts 160-161 open and the contacts 160-162 close. The secondary clock motor SM¹¹ stops due to de-energization of line wire L¹ and if the secondary clock was less than fifty-nine seconds fast the contacts 163-164 of the secondary clock will not yet have opened. The application of the regulated alternating current frequency to the high wire H¹ causes the motor M¹ of the secondary clock to be operated to cause the minute shaft (1 R. P. H.) 142² to be driven at about sixty times normal speed. This high speed rotation of the shaft 142² and cam K¹³ will, however, only continue until the contacts 163-164 operated by this cam K¹³ open. The secondary clock may therefore be slow as much as fifty-nine minutes and be brought to the end-of-hour position during the last minute of actual time as indicated by the master clock. When the master clock now reaches the end-of-hour or sixty minute position, the contacts 160-162 open and the contacts 160-161 reclose after which the secondary clock will run in exact synchronism with the master clock until the fifty-nine minute position of both clocks is reached providing there has been no current cessation. If a current cessation occurs during a certain hour and it does not exceed fifty-nine minutes the secondary clock will be corrected during the sixtieth minute of such hour. Obviously, if desired, corrections of longer outages than one hour may be corrected if the discs or cams K¹² and K¹³ are driven by two hour or three hour shafts.

Fig. 1A illustrates how secondary clocks, such as shown in Fig. 1, may be manually corrected. Let us assume that a person has tuned his radio set to receive the usual Arlington or any other time signal audible over such set. He will depress the push button PB from one to several minutes before the end of the hour as a result of which all secondary clocks will assume the sixty minute or end-of-hour position. When he hears the sound manifesting the end-of-hour period he will release the push button PB as a result of which all secondary clocks will again be operated at normal speed and will be correct. A plurality of secondary clocks may be connected in multiple and corrected in like manner.

Fig. 2.—Structure.—The secondary clock of Fig. 2 is identical to the secondary clock of the system shown in Fig. 1 except for the addition of the rectifiers RI³ and RI⁴ and transformers T¹³ and T¹⁴. These rectifiers RI³ and RI⁴ and transformers T¹³ and T¹⁴ are really filtering apparatus so that it can still be said that the secondary clocks of Figs. 1 and 2 are identical.

Referring to the master clock of Fig. 2, this clock is an escapement clock in which the pendulum is not braked like it is in Fig. 2 of my patent No. 2,359,973 granted Oct. 10, 1944, but is con-

trolled or regulated so as to at times run faster or slower than its normal adjusted correct time measuring operating rate. In this construction, which has been shown very conventionally, there is preferably provided a permanent magnet PM which has leakage poles of soft iron 170 projecting inwardly from the poles of the permanent magnet. It is also provided with soft iron extensions 171. This permanent magnet is placed directly below the pendulum 172 having a soft iron bob 172^a and the pendulum is then adjusted to keep correct time. The leakage poles are provided with a sucking winding 173, so to speak, which is at times energized by direct current derived from the regulated alternating current system through the medium of a rectifier RI⁵ and flowing through the front contact 179 of relay R⁵ and the front contact 174 of the relay R⁴. The flow of this current is in such a direction through the winding 173 that the magnetomotive force produced thereby aids the magnetomotive force of the permanent magnet and causes a large part of the flux emitted by said permanent magnet to be diverted away from the pendulum so that gravity is no longer magnetically aided to any appreciable extent and the pendulum operates at a lower frequency. In a similar manner the soft iron extensions 171 are provided with boosting windings 176 and 177 which when energized by direct current derived through the rectifier RI⁵ through the front contact 179 of relay R⁵, and the back contact 174 of relay R⁴ causes the apparent strength of the permanent magnet PM to be increased thereby still further magnetically aiding gravity and causing the pendulum to operate at a faster rate or frequency. The windings 173, 176 and 177 are when energized so poled as to aid the permanent magnet so as to avoid weakening of the permanent magnet as might be the case if they were bucking its magnetomotive force.

The relay R⁴ is so controlled that it is deenergized when the main spring 178 is especially fully wound up, that is, is wound up to a point where contacts 182-183 open, as it would be if the escapement did not quite keep up with the synchronous winding motor SM¹² and when deenergized it speeds up the escapement clock for reasons above given. The relay R⁴ is however also deenergized when the contact 182 is dead by reason of being out of contact with the contact pin 180. This control of the relays R⁴ and R⁵ is accomplished by connecting the pin 180 electrically to the gear 181, which in turn is connected by the brush 186 directly to the out-put side of rectifier RI⁵ and by feeding either the spring contact 182 alone or both of the contact springs 182 and 183 with energy from this rectifier. The spring contact 182 is connected to relay R⁵ through the medium of a first slip ring and the contact 183 is connected to the relay R⁴ through the medium of a second slip ring by a wire passing through a hole in the first slip ring. If the main spring 178 is fully wound the contacts 180-182 are closed with contacts 182 and 183 still in engagement, thus energizing relays R⁴ and R⁵, but if the main spring is slightly over-wound because the escapement 172-175 is running slower than the winding motor, that is, is running slower than the cycle passage of the alternating current, the relay R⁴ drops although the relay R⁵ remains energized, thereby causing the pendulum to be speeded up. Putting this in different words, after a temporary current cessation both of the relays R⁴ and R⁵ are in retracted conditions. When the main spring is fully wound the relays R⁴ and R⁵

pick up and by closure of their front contacts 174 and 179 energize the sucking winding 173 thereby by reducing from normal the downward pull on the pendulum 172. This causes the pendulum to run abnormally slow and causes winding motor SM¹², which was substituted for the winding motor SM¹³ when the relay R⁵ picked up, to gain with respect to the escapement 172—175, resulting in the opening of contacts 182—183 and in the deenergization of relay R⁴. With the relay R⁴ now deenergized the boosting windings 176—177 are energized thereby causing the escapement to run a little fast resulting in picking up of relay R⁴. This relay R⁴ therefore periodically picks up and drops to maintain the escapement in synchronization with synchronous motor driven winding apparatus. The worm wheels 228 and 229 and the worms 230 and 231 have such a gear ratio that the winding shaft 242 operates at exactly 1 R. P. H. when the low speed synchronous motor SM¹² operates at synchronous speed from alternating current of regulated frequency and will operate at exactly 3 R. P. H. when the high speed synchronous motor SM¹³ operates at synchronous speed from the regulated source of alternating current. The gear ratio from main spring gear 181 to the shaft 233 is one to one, because gears 181 and 234 have the same number of teeth and pinions 239 and 239^a have the same number of teeth. In other words, when the pendulum 172 operates at correct speed and the winding shaft is rewound by the low speed synchronous motor SM¹² the shafts 242 and 233 operate at the same speed of 1 R. P. H. The master clock MC² also includes a rectifier RI⁶ for at times applying pulsating current of negative polarity to the secondary clocks.

Operation Fig. 2.—Under normal conditions, namely, when alternating current is present and when there has not been a current cessation for some time, the master clock MC² is fully wound with the relay R⁵ energized and through its front contact 185 holds closed an energizing circuit for the low speed synchronous winding motor SM¹². The relay R⁴ will, of course, be at times energized and at other times deenergized to cause the escapement mechanism to run an average speed such that the contacts 182—183, for reasons already explained, remain at the point of barely touching. Between the zero and the fifty-nine minute position of the master clock as reflected by contacts 187—188—189, and by clock hand 190, pulsating current of positive polarity is derived from the regulated alternating current source through rectifier RI⁵ and is applied to the line wire H²—L². This current is blocked by the rectifier RI⁴ but flows freely through the rectifier RI³ and energizes the transformer T¹³. The secondary winding of this transformer in turn has alternating current of the same frequency (60 cycle) induced therein, which alternating current energizes the synchronous motor SM¹¹. The pulsating current of course returns to the source over the common return wire C². As explained in connection with Fig. 1 the synchronous motor SM¹¹ through gears 192—195 (see Fig. 1) drives the shaft 142² and the clock hand 191 exactly at the rate of 1 R. P. H. when sixty cycle current of regulated frequency is applied thereto, the gears 157—158—159 preferably having sufficient friction so that they will not be rotated by motor SM¹¹.

At the fifty-nine minute position of the master clock the contact 188 slips off of the cam K¹⁴ thereby causing contacts 187—188 to open and

contacts 187—189 to close. This results in the application of pulsating current of negative polarity to the line wire H²—L². This current upon reaching the secondary clock is blocked by the rectifier RI³, but flows freely through the rectifier RI⁴ and energizes the primary winding of transformer T¹⁴. The secondary winding of transformer T¹⁴ in turn energizes the synchronous motor M¹ or an induction motor, through a circuit including contacts 163—164. This motor M¹ drives the shaft 142² and clock hand 191 at substantially sixty times the speed they are driven by synchronous motor SM¹¹, so that the secondary clock may be driven to the sixty minute position where the contacts 163—164 open to stop motor M¹. This occurs during the last minute of the hour as reflected by the master clock MC². That is, a clock that is slow to the extent of about fifty-eight minutes may be corrected. Also, a clock that is fast less than one minute will be corrected. At the end of the hour (sixty minute position) of the master clock the contact 187 also slips off of the cam K¹⁴ as a result of which contacts 187—188 close and contacts 187—189 open, so that the secondary clocks all start from the sixty minute position in synchronization and operate again at the normal rate. It is thus seen that a fast clock will be corrected and that even though a power failure of fifty-eight minutes occurs the secondary clocks will be advanced. Also, it will be noted since both of the windings associated with the permanent magnet PM are deenergized during a current cessation and also during the rewinding operation that the master clock will during this time be adjusted to normal speed adjustment, and therefore will keep very good time. It should be observed that rewinding motor SM¹³ has two-pole characteristics whereas synchronous motor SM¹² has six-pole characteristics. Therefore the main spring 178 is rewound at three times normal rate so long as A. C. power is available with the relay R⁵ assuming its deenergized position. The clock therefore operates unregulated only during one and one-half times the duration of the current cessation. The indicating lamp 197 indicates when the secondary clock S² is being corrected.

Fig. 3.—Construction and operation.—In Fig. 3 has been illustrated a two circuit two speed single stator single rotor synchronous motor 2SM¹⁹ that may be used for clock correcting purposes or may be substituted for motors SM¹² and SM¹³ of Fig. 2.

This two-speed synchronous motor 2SM¹⁹ comprises two generally U-shaped stator cores 340 and 341 constructed of soft iron laminations. One pole, namely, the rearward pole with respect to the direction of rotation, of each of these U-shaped cores 340 and 341 is bifurcated and provided with a shading coil 342 to cause such direction of rotation. The ends of the poles of these U-shaped cores 340 and 341 are rounded to leave a small uniform air-gap between them and the tempered steel rotor 345 and are so spaced as to constitute a four pole construction in which alternate poles are shaded for the same direction of rotation and so that the shaded portion of a shaded pole lies adjacent the other pole of the same core 340 or 341.

If now these cores are so excited from a source of alternating current that adjacent poles of different cores have like instantaneous magnetic polarities we have a typical two-pole motor stator of which each pole belongs half to one core 340 and half to the other core 341 and which two poles each has a single shading coil to produce

clockwise rotation of a magnetic field. This two-pole magnetic field rotating in a clockwise direction produces hysteresis torque in the rotor 345 tending to drag this rotor with it. As the rotor approaches its synchronous speed of 3600 R. P. M. the rotor due to the path across it of low reluctance and including the two spokes in series, having in multiple therewith two rim portions, locks in with this magnetic field, so that the rotor operates at 3600 R. P. M., assuming a six¹⁰ cycle alternating current source.

If now the stator cores 340 and 341 are so magnetically excited from such a source of alternating current that adjacent poles of different cores have opposite instantaneous magnetic polarities we have a four-pole stator of which two adjacent poles belong to one core member 340 and the other two poles belong to the other core member 341. This four-pole magnetized structure has alternate poles only shaded, that is, has either the north poles or the south poles shaded for clockwise rotation for a particular magnetic wave of a magnetic cycle. This four-pole magnetic field will of course rotate only at a speed of 1800 R. P. M. and will tend to drag the rotor 345 with it. When the rotor 345 approaches synchronous speed it will lock in, so to speak, with this rotating magnetic field. This locking-in effect is produced by the four slots 346 cut radially into the rotor 345 from the outside and causes the rotor to operate at 1800 R. P. M.

In order to increase the amount of alternating current flowing in the shading rings 342 and correspondingly increase the lagging magnetic flux produced thereby the pole pieces are provided with extensions of magnetic material 340^a and 341^a. By looking at the stator structure of Fig. 3 it will be seen that if the stator is magnetized to produce a two-pole magnetic field the usual shading is afforded but that when the stator is magnetized to produce a four-pole magnetic field only two of the four poles are provided with shading coils. This has been done purposely, because if the other two poles had been bifurcated and shading rings had been provided these additional shading rings would have produced harmful effects when the magnetic structure is excited to produce a two-pole magnetic field, in that such additional shading rings would lie in the middle of the unshaded portion of each of the two poles.

In order to produce two-pole or four-pole magnetization of the core structure 340—341 the core 340 is preferably provided with a plane helical coil 347 and the core 341 is provided with a helical coil 348—349 having a center tap 350. This center tap is preferably connected to one terminal of the coil 347 the other terminal of this coil 347 being connected to the "common" wire in the particular system in which the motor 2SM¹⁹ is used. Each of the coils 347, 348 and 349 preferably has the same number of turns so that the magneto-motive force from pole to pole of the two cores 340 and 341 is the same irrespective of which of the two circuits is energized. It is thus seen that if alternating current is caused to flow from the wire "low" to the wire "common" four-pole magnetization will result causing the rotor to operate at 1800 R. P. M., but if alternating current is caused to flow from the wire "high" to the wire "common" two-pole magnetization results, the magnetic polarities for four-pole magnetization and for two-pole magnetization of the core 341 having been illustrated by the solid letters N and S and the dotted letters N and S, respectively. Under normal conditions the motor

2SM¹⁹ will be energized to constitute a four-pole motor, but it will be energized to constitute a two-pole motor when a secondary clock is to be advanced or a main spring is to be wound up at double speed.

If the motor 2SM¹⁹ is substituted for the wiring and motors SM¹² and SM¹³ the wire "low" will be connected to front contact 185 of relay R⁵, whereas the wire "high" will be connected to back contact 185 of this relay. The gear ratio of the winding gears will remain the same but the time required for the rewinding to catch up will be increased.

Referring to the drawings it should be understood that the various inventions and the various forms illustrating the same general invention have been shown specifically in some instances for the purpose of explaining their principles of operation and not with any attempt of limiting them to this particular construction. Referring to Figs. 1 and 2, for instance, the two embodiments of master clocks illustrated therein, although they have been illustrated as master clocks and are particularly applicable to perform a master-clock function it should be understood that they may be used as a mantle clock of the sustained power type. In Fig. 1 the condenser N is used to dampen out the direct current ripples produced by the rectifier R¹², so that the direct current flowing in the coil 155 is substantially continuous. In each form of the invention illustrating a clock system two secondary clocks have been illustrated. One of these secondary clocks shows its outside appearance whereas the other shows conventionally its internal construction. The two speed motor of Fig. 3 may be used in place of the rewind motors SM¹² and SM¹³ of Fig. 2. Having thus shown and described a number of embodiments of the present invention it is desired to be understood that the invention is not limited to these particular constructions except as demanded by the scope of the following claims.

What I claim as new is:

1. In an alternating current electric clock system, the combination with a secondary clock comprising a housing mounted for rotation about an axis, a shaft projecting from said housing rotatable with respect to said housing about said axis, reduction gearing in said housing, a first synchronous motor for rotating said shaft through the medium of said gearing without rotating said housing, a gear train, a second synchronous motor for rotating said housing and said shaft together through the medium of said gear train but at a different speed, and means including a master clock for at times energizing said first synchronous motor and for at other times energizing said second synchronous motor.
2. In an alternating current electric clock system, the combination with a secondary clock comprising a housing mounted for rotation about an axis, a shaft projecting from said housing rotatable with respect to said housing about said axis, reduction gearing in said housing, a first synchronous motor for rotating said shaft through the medium of said gearing without rotating said housing, a gear train, a second synchronous motor for rotating said housing and said shaft as a unitary structure through the medium of said gear train but at a different speed, means including a master clock for at times applying energizing current to said first synchronous motor and for at other times applying energizing current to said second synchronous motor.

contacts included in series with one of said synchronous motors and means operated by said shaft for opening said contacts when said shaft assumes a predetermined chronological condition.

3. In an alternating current electric clock system, the combination with a secondary clock comprising a clock hand, of two gear reduction gear trains, a synchronous alternating current motor for driving said clock hand at a speed to substantially correctly manifest the passing of time through the medium of one of said gear trains, another alternating current motor for driving said clock hand at a relatively much higher speed through the medium of the other of said gear trains, contacts controlled by said secondary clock which are open only for a short time at the beginning of each rotation of said clock hand, a master clock, a source of alternating current of regulated frequency regulated to correctly manifest the passing of time, two circuits extending from said master clock to said secondary clock, a shaft for said master clock, and contact mechanism operated by said shaft to close one of said circuits including said alternating current source and said synchronous alternating current motor during the greater initial portion of each revolution of said shaft and for closing said other circuit including said source of alternating current, said contacts and said another alternating current motor during a final small portion of each revolution of said shaft, whereby said secondary clock is operated at normal speed during the greater initial portion of a unit of time and is operated at a relatively much higher speed near the end of said unit of time but only until said hand reaches its end of revolution position.

4. In an electric clock system, the combination with a source of alternating current having its frequency regulated to correctly manifest the passing of time; a master clock including means for rotating a shaft to correctly manifest the passing of time as determined by said alternating current and which means upon cessation of said current rotates said shaft to substantially correctly manifest the passing of time; a secondary clock including a time shaft, a time indicator rotated by said shaft, two gear trains for driving said shaft, two alternating current circuits, an alternating current synchronous motor for driving said time shaft through the medium of one of said gear trains at a speed to correctly manifest the passing of time when energized from said alternating current source, contacts operated by said time shaft and opened during an initial increment of a revolution of said time shaft, another alternating current motor for driving said time shaft at a relatively high speed through the medium of the other of said gear trains when energized by alternating current from said source, contact mechanism associated with the shaft of said master clock for energizing said alternating current synchronous motor from said alternating current source through one of said circuits during the first greater part of each revolution of such shaft and for energizing said another alternating current motor from said alternating current source through the other of said circuits and through said contacts during a final small part of each revolution of such shaft of said master clock.

5. In an electric clock system, the combination with a source of alternating current having its frequency regulated to correctly manifest the passing of time; a secondary clock comprising a

clock-hand, two speed-reduction gear trains, a synchronous motor for driving said clock hand through the medium of one of said gear trains to correctly manifest the passing of time when such synchronous motor is energized from said source of current, another alternating current motor for driving said hand through the medium of the other of said gear trains at a relatively much faster rate when such another alternating current motor is energized from said source, contacts controlled by said secondary clock and open during an initial portion of each revolution of said clock hand and included in series with said another alternating current motor, and means for correcting said secondary clock effective to open the energizing circuit for said synchronous motor and closing the circuit for said another alternating current motor before said clock-hand reaches the end of a revolution and for again opening the circuit for said another alternating motor at the point where it was closed by said last mentioned means and reclosing the circuit for said synchronous motor at the exact time as is manifested by said clock-hand when at the end of a revolution, whereby the said circuit for said another alternating current motor is actually opened at another point by said contacts when said clock-hand reaches its end-of-revolution position.

6. In an alternating current electric clock system, the combination with a secondary clock comprising a housing mounted for rotation about an axis, a shaft projecting from said housing rotatable with respect to said housing and coaxial with said axis, reduction gearing in said housing, a first synchronous motor for rotating said shaft with respect to said housing through the medium of said gearing and without rotating said housing, a gear train, means including a second synchronous motor for rotating said housing, said gearing and said shaft in fixed relationship with each other and through the medium of said gear train but rotating said shaft at a different speed than when rotated by said first synchronous motor, and means for at times energizing said first synchronous motor and for at other times energizing said second synchronous motor.

7. In an alternating current electric clock system, the combination with a secondary clock comprising a clock hand, of two gear reduction gear trains, a synchronous alternating current motor for driving said clock hand at a speed to substantially correctly manifest the passing of time through the medium of one of said gear trains, an alternating current motor for driving said clock hand at a relatively much higher speed through the medium of the other of said gear trains, contacts controlled by said secondary clock which are open only for a short time at the beginning of each rotation of said clock hand included in series with said alternating current motor, two circuits extending to said secondary clock, a source of alternating current having its frequency regulated to correctly manifest the passing of time, and means for including said source in series in said circuits one at a time.

8. A secondary clock comprising, a housing mounted for rotation about an axis, a time shaft projecting from said housing and mounted for rotation with respect to said housing about said axis, time indicating means driven by said time shaft, reduction gearing in said housing, a synchronous motor for rotating said time shaft at a particular speed through the medium of said

13

reduction gearing without rotating said housing, a gear train, means including an alternating current motor for rotating said housing said gearing and said time shaft as a unitary structure and without operating said gearing with respect to said housing and through the medium of said gear train and rotating said time shaft at a different than said particular speed, contacts included in series with said alternating current motor, and means driven by said time shaft for opening said contacts when said time shaft assumes a predetermined chronological condition.

OSCAR H. DICKE.
